APPARATUS FOR DETECTING
COMBUSTIBLE GASES

John N. Burdick, Buffalo, N. Y., assignor to The
Linde Air Products Company, a corporation of
Ohio

Application March 18, 1938, Serial No. 196,719

4 Claims. (Cl. 177—311)

The invention relates to a method and apparatus for the continuous and automatic detection of predetermined concentrations of carbonaceous constituents in gases or mixtures thereof and is particularly adapted for detecting the presence of hydrocarbons in so-called industrial atmospheres.

For the sake of simplicity and clarity, the present invention will be described in connection with the determination of hydrocarbons in certain industrial atmospheres, for example, atmospheres which are present in or about operations involving the production of liquefied gases. However, it will be apparent as the description proceeds that the invention is also applicable to various other situations.

In the manufacture of liquefied oxygen, certain concentrations of combustible impurities such as hydrocarbons in the air supply, if not detected in time, may lead to serious explosions. Apparently, such explosions are caused by the reaction between oxygen and the hydrocarbons which have accumulated in some part of the system and then have been ignited, spontaneously or otherwise. Analytical methods for determining the presence of hydrocarbons in the air supply prior to its introduction into the system have heretofore been in use but for certain reasons these have been unsatisfactory. In the most common of such methods the hydrocarbons are converted to carbon dioxide, the carbon dioxide then absorbed in an alkaline solution and the solution finally titrated to determine its carbon dioxide concentration. Such a method is particularly unsatisfactory in industrial operations because it measures the actual amount of carbon dioxide only over a lengthy period. Consequently, in the event of a sudden influx of hydrocarbons in the air supply no knowledge of such a dangerous condition would be available until, perhaps, damage had been done. Further, the method is limited to intermittent operation and requires the presence of an operator during each determination. Finally, the apparatus necessary to carry out the method is bulky and requires considerable care and attention.

An object of this invention is to provide a method, free from the above disadvantages, for the continuous and automatic detection of predetermined concentrations of carbonaceous constituents in gases or mixtures thereof.

Another object of the invention is to provide a compact and efficient apparatus suitable for carrying out the method of the invention.

These and other objects are attained in the method of the present invention which comprises the steps of purifying a gas or gaseous mixture, containing one or more carbonaceous constituents, of its objectionable acidic components; oxidizing said constituents to carbon dioxide;

intimately mixing said carbon dioxide with a solution, the color of which, by virtue of the presence of a soluble dye (indicator), varies in a definite degree with the carbon dioxide concentration, and automatically detecting the color variations in said solution caused by an increase in carbon dioxide above a predetermined concentration. It has been found that the color variations in said solution may be continuously detected by means of a photo-electric device responsive to such variations and that such a device may be connected, with or without current amplifiers, to a suitable alarm signal so that any increase in carbon dioxide concentration above a predetermined value will automatically activate the alarm signal.

The invention will be more fully described in connection with the attached drawing in which:

Fig. 1 is a diagrammatic side view of a preferred form of an apparatus embodying the invention with one wall of the enclosing cabinet removed to disclose the interior;

Fig. 2 is a fragmentary sectional diagrammatic view, taken at 2—2 of Fig. 1, showing in detail the construction of an absorber B; and

Fig. 3 is a wiring diagram indicating the electrical circuit of the apparatus shown in Figs. 1 and 2.

To explain the respective function of the separate parts of the preferred form of the detector apparatus shown in the attached drawing, the operation of such an apparatus for the detection of hydrocarbons in air will be described by way of example.

Referring to Fig. 1, the entire apparatus is for convenience contained in a single cabinet 29. The air sample to be tested, at a pressure above atmospheric, is introduced to the detector apparatus through an inlet tube 10, connected to a

safety trap 11, containing mercury or other suitable liquid, which serves to protect the apparatus from the building up of an excessively high pressure, to and through a trap 12 where carbon dioxide and other acidic gases are removed. The trap 12 may suitably contain a granular, highly absorbent material consisting of a mixture of sodium hydroxide and asbestos. After leaving the trap 12, the gas sample is passed through a second trap 13 containing a material capable of

absorbing ammonia, such material preferably consisting of silica gel moistened with dilute sulphuric acid. From the second trap 13, the sample passes to and through a saturator A which saturates the gas with water vapor. The saturator A suitably consists of a helical tube 14, constantly filled by water from a chamber 50 supplied, in turn, by a liquid levelling reservoir 15. The gas sample is introduced into the saturator A through a nozzle 51.

After being thus saturated with water, the gas

sample is led through a metal conduit 52 to a combustion tube 48 in which any hydrocarbons present in the sample are burned to carbon dioxide. For this combustion tube 48 I prefer to employ a high-chromium-alloy steel tube which contains oxidized copper wire as a catalyst. The combustion tube is externally heated in a furnace 16 to a temperature of about 850° C. As indicated in Fig. 3, the furnace 16 may be electrically heated, the heating current being controlled for instance by a resistance 45 and indicated by a meter 36.

The gas sample, now consisting entirely of oxygen, nitrogen, and carbon dioxide, is passed from the combustion tube 48 through a metal conduit 53 and a glass tube 54 into an indicator solution contained in an absorber B. The absorber B, details of which are shown in Fig. 2, is made of glass and comprises a reservoir 20, a sight chamber 26, provided with two flat, parallel, opposed walls and a helical tube 17, all of which parts are kept substantially full of indicator solution by connection through a tube 28 and a three-way cock 27 to a liquid levelling chamber 18. The gas sample passes into the helical tube 17 through a nozzle 38 and bubbles up through the tube 17 and the reservoir 20 out into the atmosphere. The motion of the gas passing through the helical tube produces a circulation of the indicator solution up through the helical tube 17 to the reservoir 20 and down through the sight chamber 26 to the bottom of the helical tube 17. Solution may be drained from the absorber B by opening the cock 27.

An indicator solution which I prefer for the purpose of the present invention is characterized by an easily distinguishable color change in the alkaline range, good chemical stability and color stability, and capable of entering into reversible reaction with dilute concentrations of carbon dioxide in oxygen-nitrogen mixtures. It is particularly important that the absorption of carbon dioxide be reversible, inasmuch as the rapid and continuous indication of the concentration of carbon dioxide depends upon a rapid and reversible color change of the solution as gas samples of different carbon dioxide content bubble through it. Consequently, as a result of testing numerous solutions, a water solution of sodium bicarbonate and xylanol blue (p-xylanol sulphone phthalein), which is blue at a pH of 9.2 and above, and yellow at a pH of 8.0 or lower was found to fulfill the above requirements. In the preparation of the indicator solution it is desirable to prepare the following two separate solutions which are intermixed to make a single solution.

1. Sodium bicarbonate aqueous solution, 0.0005 normal.

2. A saturated aqueous solution of xylanol blue containing approximately 0.67 milligram of xylanol blue per cubic centimeter of solution. The proportions of the two solutions to be intermixed may be determined by the usual methods of preparing pH indicator solutions. Although I prefer to employ a xylanol blue indicator solution, other indicator solutions, some of which are characterized by a color change other than from blue to yellow, may also be suitably employed. Further, I do not wish to be restricted to the specific proportions herein shown, as indicator solutions having their ingredients in proportions other than these will function satisfactorily.

When a predetermined dangerous concentration of hydrocarbons exists in the sample being tested, the indicator solution in the absorber B

changes from a blue to a yellow color as the carbon dioxide gas reacts with the solution. When the hydrocarbon content of the sample returns to its value for normal operation, the color of the indicator solution likewise returns to its original blue color. The change of color may be observed visually, and is also used to actuate an automatic alarm in the following fashion. A beam of light from a light source 25 is directed by a suitable lens system through the flat, parallel, opposed glass walls of the sight chamber 26, and through the indicator solution contained therein, onto the light receiving element of a photo-electric cell 21. Variations in the light transmitting power of the solution are detected by the photo-electric cell and thereby translated into variations in an electrical current. The light source 25 may consist of a 50 watt 120 volt projection lamp, and the lens system 23 may be any conventional system suitable for focusing the light image in the center of the sight chamber 26. As shown in Fig. 3, the light source 25 is provided with electric current by a transformer 30, and a variable resistance 19 is provided to control the light intensity.

The operation of the photo-electric cell 21 and apparatus ancillary thereto is indicated in Fig. 3. The cell 21 is preferably of the voltaic type, and this is the type shown in Fig. 3, but other types may be used if suitable changes in the auxiliary apparatus are made. The voltaic type cell 21 generates its own current when exposed to light in the visible spectrum and is used to operate a relay 33 of the D'Arsonval galvanometer type or an equivalent relay. A thermostat 35 and an electrical resistance heater 31 controlled by the thermostat 35 maintain the photo-electric cell 21 at a temperature conducive to efficient operation, suitably a temperature between 90° F. and 100° F. A resistance 39 is inserted in series with the cell 21 and the relay 33 to limit the flow of electric current.

The relay 33 is used to control a circuit including an alarm horn 22 or other warning signal. Such circuit suitably comprises a source of direct current, such as a transformer 46 and a rectifier 47, a power relay 40, the horn 22, and electric current leads 24 containing switches 37 and 43.

When the concentration of carbon dioxide in the gas sample reaches a dangerous concentration, the color of the indicator solution in the sight chamber 26 changes from blue to yellow. This change in color correspondingly alters the character of the light beam passing through the sight chamber 26 from the light source 25 to the photo-electric cell 21. The electric current generated by the cell 21 is altered by such change in light, and the alteration in current closes the relay 33, permitting direct current to flow through, and to close, the power relay 40. The closing of the power relay 40 causes the alarm horn 22 to sound.

A relay 41, normally open, is used in series with the light source 25 so that, if the light source fails, the relay 41 will close and sound the horn 22. A warning lamp 44 is used to indicate that the switch 43 is open and no current is being supplied to the alarm horn circuit. A lamp 34 is placed inside the cabinet 29 for convenience in visually inspecting the color of the indicator solution in the absorber B.

The relays 33, 40, and 41, the rectifier 47, and the transformers 30 and 46, are for convenience housed together in a suitable power-unit cabinet P.

If desired, direct current may be used to actu-

ate the alarm horn 22, the lamps, and the furnace, in which case resistances may be substituted for the transformers 30 and 46, and the rectifier 47 will not be needed.

While I have disclosed in detail a preferred embodiment of my invention, it is obvious that without departing from the invention, many other embodiments may be made to adapt the method and apparatus of the invention to numerous situations. For example, hydrocarbons in any non-combustible gas such as argon may readily be detected if a suitable amount of oxygen is added to the sample. For the detection of carbonaceous constituents in combustible gases, means, other than a high temperature catalyst, may be used to promote the oxidation to carbon dioxide. For example, carbon monoxide may be oxidized by the use of iodine pentoxide. By employing a suitable catalyst and temperature, certain combustible gases may be detected in the presence of other combustible gases when the latter gases are not affected under the conditions of oxidation. Also, the method and apparatus may readily be adapted to detect the presence of carbon dioxide in atmospheric gases, hydrogen, or hydrocarbon gases, merely by omitting the combustion step.

I claim:

1. An apparatus for automatically detecting, in the air supply for processes involving high compression of such air, the presence of oxidizable carbon dioxide-forming compounds in a concentration in excess of a predetermined safe limit, which comprises, in combination, means for continuously withdrawing a sample stream of such air; means for continuously treating said sample stream to oxidize to carbon dioxide, all oxidizable carbon dioxide-forming compounds present therein; a reversible absorbent for carbon dioxide which is capable of yielding up carbon dioxide to, or of absorbing carbon dioxide from, said sample stream in response to changes in concentration of carbon dioxide in said treated sample stream, and thus in accordance with corresponding changes in concentration of said compounds in said air supply, said absorbent also being capable of transmitting energy in varying degree depending on its carbon dioxide content and undergoing relatively abruptly a substantial change in energy transmitting properties in the region of carbon dioxide content thereof corresponding to said predetermined limit of concentration of oxidizable carbon dioxide-forming compounds in said air supply; means for continuously bringing said treated sample stream into intimate contact with said absorbent; means for transmitting energy through said absorbent; means, responsive to variations in energy transmitted through said absorbent, for continuously receiving at least a part of such transmitted energy; and signalling means, actuatable by said energy-responsive means, for indicating whenever said absorbent abruptly undergoes substantial change in energy transmitting properties in said region.

2. An apparatus for automatically detecting, in the air supply for processes involving high compression of such air, the presence of hydrocarbon in a concentration in excess of a predetermined safe limit, which comprises, in combination, means for continuously withdrawing a sample stream of such air; means for continuously treating said sample stream to oxidize to car-

bon dioxide all hydrocarbon present therein; a reversible liquid absorbent for carbon dioxide which is capable of yielding up carbon dioxide to, or of absorbing carbon dioxide from, said sample stream in response to changes in concentration of carbon dioxide in said treated sample stream, and thus in accordance with corresponding changes in the hydrocarbon concentration in said air supply, said absorbent also being capable of transmitting light in varying degree depending on its carbon dioxide content and undergoing relatively abruptly a substantial change in light transmitting properties in the region of carbon dioxide content thereof corresponding to said predetermined limit of concentration of hydrocarbon in said air supply; means for continuously bringing said treated sample stream into intimate contact with said absorbent, means for transmitting light through said absorbent; means responsive to variations in light transmitted through said absorbent for continuously receiving at least a part of such transmitted light; and signalling means including a photoelectric cell for indicating whenever said absorbent abruptly undergoes substantial change in light transmitting properties in said region.

3. An apparatus as defined in claim 2 in which the reversible absorbent for carbon dioxide is an alkaline solution containing an indicator capable of undergoing a substantial change in color at a pH from about 8.0 to about 9.2.

4. An apparatus for automatically detecting, in the air supply for processes involving high compression of such air, the presence of hydrocarbon in a concentration in excess of a predetermined safe limit, which comprises, in combination, an inlet tube constructed and arranged for continuously withdrawing a sample stream of such air; a heated combustion tube containing a combustion catalyst for continuously treating said sample stream to oxidize to carbon dioxide all hydrocarbon present therein; an absorber vessel containing a water solution of sodium bicarbonate acting as a reversible liquid absorbent for carbon dioxide which is capable of yielding up carbon dioxide to, or of absorbing carbon dioxide from, said sample stream in response to changes in concentration of carbon dioxide in said treated sample stream, and thus in accordance with corresponding changes in the hydrocarbon concentration in said air supply, said absorbent also containing xylene blue which makes said absorbent capable of transmitting light in varying degree depending on its carbon dioxide content and undergoing relatively abruptly a substantial change in light transmitting properties in the region of carbon dioxide content thereof corresponding to said predetermined limit of concentration of hydrocarbon in said air supply; means for continuously bringing said treated sample stream into intimate contact with said absorbent, means for transmitting light through said absorbent; means including a photoelectric cell responsive to variations in light transmitted through said absorbent for continuously receiving at least a part of such transmitted light; and signalling means controlled by said photoelectric cell for indicating whenever said absorbent abruptly undergoes substantial change in light transmitting properties in said region.

JOHN N. BURDICK.
